CLAIM

The ornamental design for a fire extinguisher discharge valve, as shown and described.

DESCRIPTION

FIG. 1 is a perspective view of a fire extinguisher discharge valve, showing our new design;

FIG. 2 is a side view thereof;

FIG. 3 is another side view thereof;

FIG. 4 is a rear view thereof;

FIG. 5 is a front view thereof;

FIG. 6 is a top view thereof; and,

FIG. 7 is a bottom view thereof.

The evenly spaced broken lines in the drawings illustrate portions of the fire extinguisher discharge valve and form no part of the claimed design.
